UNITED STATES PATENT OFFICE.

MARY E. CHAMBERLAIN, OF MUSKEGON, MICHIGAN.

CUSPIDOR.

No. 860,904.

Specification of Letters Patent.

Patented July 23, 1907.

Application filed December 29, 1906. Serial No. 350,091.

To all whom it may concern:

Be it known that I, MARY E. CHAMBERLAIN, a citizen of the United States, residing at Muskegon, in the county of Muskegon and State of Michigan, have invented new and useful Improvements in Cuspidors, of which the following is a specification.

This invention relates to cuspidors of the type disclosed in Patent No. 418,553, granted December 31st, 1889, to C. C. Chamberlain, and comprehends the formation of the receptacle from a blank of paper or analogous, pliable material susceptible of being plaited and folded for imparting the desired shape to the finished vessel, which may, in practice, be collapsed for shipment or storage and will retain its shape. It has been found, in practice, that the device of the patent is, owing to the peculiar formation of the plait, somewhat expensive in construction, and this owing to the cost attendant upon constructing a machine for plaiting the blank, and further, that the completed devices, when in use, do not at all times stand in proper upright position.

The present invention has for its objects to produce a cuspidor of this class by which the above noted objections are overcome, one involving a simplified mode of plaiting the blank, thus reducing the cost of the machine, with a consequent reduction in the cost of producing the article, and one wherein provision is made for the vessel standing smoothly and evenly when in use.

With these and other objects in view, the invention comprises the novel features of construction and combination of parts more fully hereinafter described.

In the accompanying drawings: Figure 1 is a top plan view of a cuspidor embodying the invention. Fig. 2 is a side elevation of the same. Fig. 3 is a view of the blank. Fig. 4 is a detail, sectional view, taken on the line 4-4 of Fig. 2.

Referring to the drawings, 1 designates the vessel or cuspidor made from a blank 2 of paper or analogous material which may be suitably waterproofed, and if desired, subjected to a fire proofing treatment.

The blank 2, which is of circular form, as shown in Fig. 3, is provided by a circular, scored line 3 with a central portion 4 adapted to form the bottom of the receptacle, said bottom being provided at its marginal edge with an annular, upwardly convexed rib 5 formed by scoring the blank along the circular lines 6 and 7, and thereafter pressing the material of the blank into shape. That portion of the blank which lies beyond the scored or indented line 3 is provided with a circular concentric scored line 12 which is formed about midway between the line 3 and the margin of the blank; said portion of the blank is also provided with a plurality of scored lines 9 and 10 extending respectively between the lines 3 and 12; and between the latter line and the margin of the blank, said lines 9 and 10 in con-

junction with the line 3 and the margin of the blank bounding a plurality of hour glass shaped sections A, the narrowest portions of which are intersected by the line 12. Additional scored lines 8, extending between the line 3 and the margin of the blank, serve as boundaries for the outwardly flaring sections B. The inner ends of the lines 8 meet the inner extremities of the lines 9 in the circular line 3; and the sections C bounded by the said lines 8, by the lines 9-10 and by the margin of the blank constitute pointed flaps which alternate with the sections A and B, each of the sections A as well as each of the sections B, being disposed intermediate two of the flaps C as will be readily seen in Fig. 3 of the drawings.

The blank constructed in this particular manner may be readily folded to the condition clearly indicated in Figs. 1 and 2 of the drawings, by upturning that portion of the blank which lies beyond the line 3 and reversely bending that portion which lies beyond the line 12; the flaps C-C being interplaited between the hour glass shaped flaps or sections A and the flaring sections B, so as to form the flanged flaring receptacle clearly indicated in said Figs. 1 and 2. The receptacle thus formed may be compressed or folded to a practically flat condition, and may be readily restored or extended by pulling the flaring portion or flange in an upward or outward direction. The receptacle will readily retain its shape, and it may be conveniently used for the purposes for which it is provided. Its construction is of such a nature that it is not readily upset causing the contents thereof to be spilled; and it may be manufactured at such a trifling expense that after serving its purpose it may be discarded and a new one provided.

Having thus described my invention, what I claim is:

1. A circular paper blank for the manufacture of sanitary spittoons provided with four circular concentric scored lines, the material of the blank between the first and the third scored lines counting from the center being offset upwardly to form an annular rib, and said blank being provided with additional scored lines extending from the third and across the fourth circular scored line to the margin of the blank and forming between them alternate hour glass shaped sections and outwardly flaring sections, and tapering pointed flaps intermediate the said hour glass shaped sections and outwardly flaring sections.

2. A sanitary paper vessel having a plaited reversely bent or flanged wall comprising alternate hour glass shaped sections and outwardly flaring sections, and flaps disposed intermediate the hour glass shaped sections and the outwardly flaring sections, said hour glass shaped sections, flaring sections and flaps being transversely scored on the line of the reversely bent flange.

In testimony whereof, I affix my signature in presence of two witnesses.

MARY E. CHAMBERLAIN.
